UNITED STATES PATENT OFFICE.

EVERETT W. FESSENDEN AND HARVEY A. DUNN, OF LYNN, MASSACHUSETTS.

INSOLE FOR BOOTS AND SHOES.

1,269,528.

Specification of Letters Patent. Patented June 11, 1918.

Application filed April 30, 1917. Serial No. 165,360.

To all whom it may concern:

Be it known that we, EVERETT W. FESSENDEN and HARVEY A. DUNN, citizens of the United States, residing at Lynn, in 5 the county of Essex and State of Massachusetts, have invented new and useful Improvements in Insoles for Boots and Shoes, of which the following is a specification.

This invention relates to an improved 10 insole for boots and shoes, the object of the invention being to provide an insole in which very thin, flimsy leather may be utilized and still the insole be firm and strong for all practical uses to which it may 15 be subjected.

The object of the invention is further to 20 provide an insole of the character set forth which is made of two pieces of sheet material, one of leather and the other of canvas or other suitable textile material, which 25 are joined together by stitches in such a manner that in the completed shoe the stitches do not show.

The invention consists in an insole constructed as hereinafter described and fully 30 set forth in the claims.

Referring to the drawings:

Figure 1 is a plan view of a blank from 35 which our improved insole is manufactured.

Fig. 2 is a transverse section of the same taken on line 2—2 of Fig. 1.

Figs. 3 and 4 are sections of the insole at different stages in the manufacture of the same.

Fig. 5 is a transverse section of the sole completed and ready to be incorporated in the manufacture of a shoe.

Fig. 6 is a plan view of the completed insole.

Fig. 7. is a section of a shoe in process of manufacture with our improved insole incorporated therein.

Like numerals refer to like parts throughout the several views of the drawings.

Our improved insole is manufactured as follows: Two pieces of sheet material, preferably canvas and thin leather, are joined together by an adhesive material, such as cement and the soles are then "dinked" 45 out of the sheet to form a sole such as that illustrated in Figs. 1 and 2, in which 10 is the textile material, such as canvas, and 50 11 is the leather.

The next step in the operation of manufacture of our improved insole consists in 55 slitting the leather portion of the insole

around the edge as at 12 and turning up a lip 13 which extends around the sole, from the shank portion around the toe. The portion 14 of the leather part 11 is then further 60 attached to the canvas portion 10 by a row of stitches 15, thus firmly uniting the canvas and the leather.

The next step in the operation is to lay 65 the lip 13 back against the portion 14 of the part 11 and join the parts 13 and 14 by cement.

The next step in the operation is to 70 turn the canvas up around its edge, from the shank portion around the toe portion of the sole to form a bead 16, this bead being turned up so that the inner side 17 of said lip is adjacent to and outside the row of stitches 15, as illustrated in Figs. 5 and 6.

The innersole is then placed upon a last 75 18, the upper 19 of a shoe is lasted in the usual manner and a welt 20 is attached to the upper and to the insole by stitches 21 which extend through said welt, upper and 80 insole, as illustrated in Fig. 7. After the welt has been attached, the outsole is attached to the welt in the usual manner, and in the completed shoe it will be seen that the stitches 15 which join the two 85 parts of the insole together will be hidden from view on the outside of the shoe; as said stitches terminate in the slit 12 they will also be invisible from the inside of the shoe. Thus the inner surface of the 90 insole of the shoe will be perfectly smooth and free from stitches, which is very desirable in the manufacture of a welt shoe, for if a row of stitches were to show on the inside of the insole of the shoe, it would 95 give the same the appearance and have all the disadvantages of what is known as the "McKay" sewed shoe.

Having thus described our invention, what we claim and desire by Letters Patent to 100 secure is:

1. An inner sole for boots and shoes having, in combination, two thicknesses of sheet material, one of said sheets of material only being turned up around its edge to form a 105 lip, and stitches extending only through said last-named sheet material adjacent the inner side of said lip and only part way through said other sheet of material.

2. An inner sole for boots and shoes having, in combination, a sheet of leather and a sheet of textile material, said sheet of tex- 110

tile material only being turned up around its edge to form a lip and stitches extending only through said sheet of textile material adjacent the inner side of said lip and only 5 part way through said sheet of leather.

3. An inner sole for boots and shoes having, in combination, two thicknesses of sheet material cemented together, one of said sheets of material only being turned up 10 around its edge to form a lip and stitches extending only through said last-named sheet of material adjacent the inner side of said lip and only part way through said other sheet of material.

15 4. An inner sole for boots and shoes having, in combination, two thicknesses of sheet material, one of said sheets of material only being turned up around its edge to form a lip, the other of said sheets of material being 20 slitted around its edge and stitches extending only through said first-named sheet of material adjacent the inner side of said lip, and only partly through said last-named sheet of material and into said slit.

25 5. An inner sole for boots and shoes having, in combination, two thicknesses of sheet material, one of said sheets of material being turned up around its edge to form a lip, the other of said sheets of material being 30 slitted around its edge and stitches extending through said first-named sheet of material adjacent the inner side of said lip, extending only partly through said last-named sheet of material and into said slit, the slit-

ted portions of said second named sheet of 35 material being joined together with adhesive material.

6. An inner sole for boots and shoes having, in combination, two thicknesses of sheet material, one of said sheets of material being 40 turned up around its edge to form a lip, the other of said sheets of material being slitted around its edge and stitches extending through said first-named sheet of material adjacent the inner side of said lip and 45 partly through said last-named sheet of material and into said slit, the slitted portions of said second named sheet of material being substantially parallel to each other.

7. An inner sole for boots and shoes having, in combination, two thicknesses of sheet material, one of said sheets of material being turned up around its edge to form a lip, and stitches extending only through said last 50 named sheet of material adjacent the inner 55 side of said lip and only part way through said other sheet of material and in a direction approximately normal to the insole faces.

In testimony whereof we have hereunto 60 set our hands in presence of two subscribing witnesses.

EVERETT W. FESSENDEN.
HARVEY A. DUNN.
